UNITED STATES PATENT OFFICE.

MAXIMILIAN WEIL, OF NEW YORK, N. Y., ASSIGNOR, BY MESNE ASSIGNMENTS, TO NATIONAL PHONE COMPANY, INC., OF NEW YORK, N. Y., A CORPORATION OF DELAWARE.

TELEPHONIC APPARATUS.

1,345,049.

Specification of Letters Patent. Patented June 29, 1920.

Application filed March 30, 1916. Serial No. 87,861.

To all whom it may concern:

Be it known that I, MAXIMILIAN WEIL, a citizen of the United States of America, residing at the borough of Manhattan, city, 5 county, and State of New York, have invented certain new and useful Improvements in Telephonic Apparatus, of which the following is a specification.

This invention relates to apparatus for use 10 in telephoning for precluding exterior emission of the telephone conversation.

An object of this invention is to provide means for precluding the emission of conversation exteriorly of the telephone, to 15 thereby attain privacy when telephoning and also to avoid disturbance or inconvenience to other parties in the same room or inclosure in which the telephone apparatus is located. A further object of the invention is to attain 20 improved aseptic conditions in the use of telephone apparatus.

It has been heretofore proposed to employ booths for inclosing telephone apparatus and the person of the user, but such arrangements are expensive, require considerable 25 floor area and are highly objectionable owing to accumulation of infectious germs, objectionable odors, etc. It also has been heretofore proposed to employ various devices 30 such as hoods, placed over the telephone transmitter, receiving the user's head or mouth while telephoning. However, such devices have been failures owing to interference effects in sound waves due to reflection and eddy voice currents within the 35 hood, loss of nasal sounds causing incomplete enunciation, etc., and also to inconvenience in use and causing septic conditions. While certain of such devices operated to 40 silence the sounds at the user's end of the telephone, they were ineffectual in attaining understandable transmitted conversation, and hence, so far as I am aware, became complete failures.

45 In accordance with my invention, the above disadvantages are for all practical purposes entirely eliminated, as will be exemplified by two desirable forms of my invention. One form of my invention is particularly adapted for use with the ordinary desk and wall types of telephones, and may be generally described as comprising a hollow body member adapted to be placed close to the mouth of the user and adapted to receive 50 the voice sounds, an acoustic dia-

phragm, and a passage or passages conveying the sounds from the interior of said hollow body member to said diaphragm, in combination with means for relieving excess air pressure and minimizing reflecting and other "echo" sound waves. Preferably, my invention also includes means related to the acoustic diaphragm for focusing the sound waves transmitted thereby onto the transmitter of the telephone. For purposes of 60 simplification in manufacture, such form of my invention is usually constructed to embody as a unitary device the hollow body member, acoustic diaphragm, the sound passages means and the anti-pressure and anti-reflection means, in which form my invention may be readily manually held in suitable spaced relation to the transmitter of the telephone. If desired, the hollow body member may be provided at its forward end 65 with a mouth piece of glass or other vitreous material, or the like, to enable the same to be cleansed by antiseptic treatment, for which purpose the mouth piece may be removably attached to the hollow body member. 70

Another form of my invention is particularly applicable to hand-set telephones including the aforesaid main features of my invention mounted conjointly onto and in spaced relation to the transmitter of the 75 hand-set.

Further objects and features of my invention will be more fully understood from the following description and accompanying drawings, in which— 80

Figure 1 is a side elevation of one form of my invention;

Fig. 2 is a longitudinal sectional elevation but showing a portion of the sound passage means removed, for sake of clearness; 95

Fig. 3 is a detail sectional view on line 3—3 of Fig. 2;

Fig. 4 is a detail plan view of the sound passage means;

Fig. 5 is a diagrammatic view, showing the 100 use of my invention with an ordinary telephone transmitter;

Fig. 6 is a detail plan view of the acoustic diaphragm shown in the above named figures; and 105

Fig. 7 is a perspective view, largely diagrammatic of another form of my invention.

Referring to Figs. 1 and 2, the hollow body member 1 is shown as substantially cylindrical in its major portion and pro- 110

vided with the mouth piece 2 adapted to receive the mouth of the user. The mouth piece 2 is shown removably attached to the hollow body member 1 by the screw-threaded joint 3. The lower portion 4 of mouth piece 2 may be advantageously brought against the chin of the user as a partial support, while the fingers of the user will encircle the exterior of the hollow body member 1 to support and direct the same in relation to the telephone transmitter. As indicated in Fig. 5, the device is held in spaced relation to the telephone transmitter 5, and the device directed so that the mean path of travel of the sound waves, as indicated by the arrowed line 6, is substantially centrally of the mouth piece of the telephone transmitter 5.

Referring further to Figs. 1 and 2, the sound passage means is shown as comprising an annular or other hollow element 7, adjustably positioned within the interior of the hollow body member 1, as by screw-threaded engagement therewith; said sound passage means 7 is provided with the transmitting passage 8, shown extending centrally therethrough and leading to the acoustic diaphragm 9 preferably mounted on resilient gaskets 10, 10, shown as a band or ring of rubber extending about the edge of the diaphragm 9 from one face thereof to the other. Upon impact of sound waves against said diaphragm 9, the same will be vibrated in consonance therewith and the resultant sound waves transmitted through the rearward exit opening 11 of the sound directing means 12. The path of the resultant sound waves is indicated by the arrowed line 6 of Fig. 5.

40 The anti-pressure and anti-interference means is shown provided with passages 13 extending generally longitudinally of the hollow body member 1 and having forwardly directed openings, then communicating with rearward transverse passages 14, then communicating with returned passages 15, then communicating with forward transverse passages 16 and then communicating with terminal passages 17. Extending rearwardly of the rearward portion of said sound passage means 7 is provided the outlet openings 18 shown as formed within an annulus 19 having an inner annular passage 20 adapted to communicate with said terminal passages 17 and communicating with the atmosphere through said openings 18. Said annulus 19 is shown assembled onto the body member 1 by screw threaded or other adjustable connection, whereby upon proper positioning of the same, the annular passage 20 will be brought into common communication with the respective terminal passages 17. Said focusing means 12 is shown as constructed integrally with said annulus 19 and jointly mounted by screw threaded engage-

ment onto said sound passage means 7, thereby regulating the degree of pressure against said gaskets 10, 10, of the acoustic diaphragm 9.

It will be noted, in the construction shown, that the circumscribing wall of the individual passages 13, 14, 15, 16 and 17, forming the respective sets of circuitous passages, is constituted by the inner face of the hollow body member 1, except that the rearward portion of each terminal passage 17 is open to the encircling groove 20. In Fig. 2 the sound passage means 7 is shown broken away to an extent of about ninety degrees of its periphery, but in construction it is continuous throughout its complete periphery and provided with smaller sets of circuitous passages, as indicated in Fig. 4.

The diaphragm 9 may be formed of metallic or other resilient or yieldable material, or of other material possessing a certain degree of porosity as well as yieldability. The configuration of the sound directing means 12 will be determined in accordance with the particular circumstances of use. The complete tests which I have made over telephone lines show the entire absence of muffled and "echo" interfering sounds while the nasal sounds are translated directly into the mouth piece of the transmitter, thereby attaining transmission over the line of the full voice waves and yielding clear and distinct enunciation at the receiving end.

It will be noted that my invention attains privacy during telephone conversation and also precludes disturbance of other parties in the same room or inclosure as the user. My invention provides in telephoning a device for private use and reserve possessing advantages similar to an individual drinking cup.

The form of my invention shown in Fig. 7 is adapted particularly for hand-set telephone use. The handle 25 is shown supporting the acoustic receiver 26 at one end and the acoustic transmitter 27 at the other end, the last-named being similar in construction to the device shown in the above described figures. When in proper position for use with the transmitter 5 of the ordinary telephone transmitter, the mean path of the voice waves indicated by the arrowed line 6 will be directed toward the mouth piece of transmitter 5, similarly as above. The ordinary receiver 28 of the telephone line may be placed upon the support 29 of the acoustic transmitter 30 comprising the amplifying passage 31 connected by means of the hollow tubing 32 with the acoustic receiver 26. The operation of my last described form is substantially the same as the forms described more fully hereinabove, excepting that the transmission of the respective sound waves are conveyed acousti-

cally from the telephone receiver to the receiving device placed adjacent the ear of the user.

From the above described forms of my invention, it will be noted that my invention possesses advantages over telephone booths in attaining acoustic conditions, privacy in conversation, reduction in space required for installation, less disturbance to outsiders, etc. The nature of operation and use of my invention gives it the relation of a pseudo-wireless telephone transmitter, and functioning in principles radically superior to prior art proposals, so far as I am aware. Whereas I have described my invention by reference to specific forms thereof, it will be understood that many changes and modifications may be made without departing from the spirit of my invention.

20 I claim:

1. Apparatus adapted for use with a sound receiving device having a member provided with a sound receiving passage, comprising a casing, means being disposed in said casing for silently receiving and transmitting articulate sound waves emitted through the mouth of the user, said casing comprising a mouth piece constructed to substantially completely inclose the mouth 25 of the user but leaving the nose of the user open to the free atmosphere, whereby the sounds emitted through the nose of the user are transmitted through the free atmosphere to said device, said casing being provided at its extreme end opposite said mouth piece with an exit opening, said exit opening when the apparatus is in use being spaced from said member through the free atmosphere.

40 2. Apparatus adapted for use with a sound receiving device having a member provided with a sound receiving passage, comprising means for silently receiving articulate sound waves emitted through the 45 mouth of the user, said receiving means comprising a mouth piece constructed to substantially completely inclose the mouth of the user but leaving the nose of the user open to the free atmosphere, whereby the sounds emitted through the nose of the user are transmitted through the free atmosphere to said device, said receiving means comprising a yieldable element, said means being provided with an exit opening, said 50 exit opening when the apparatus is in use being spaced from said member through the free atmosphere.

55 3. Apparatus for use with a sound receiving device having a member provided 60 with a sound receiving passage comprising a casing, means disposed in said casing for silently receiving sound waves emitted through the mouth of the user, said casing comprising a mouth piece constructed to 65 substantially completely inclose the mouth

of the user but leaving the nose of the user open to the free atmosphere, said casing comprising a yieldable diaphragm disposed in said casing, said casing being provided with an exit opening, said exit opening when 70 the apparatus is in use being spaced from said member through the free atmosphere.

4. Apparatus for use with a sound receiving object, comprising means for silently receiving sound waves emitted through the 75 mouth of the user, said receiving means comprising a mouth piece constructed to inclose the mouth of the user but leaving the nose of the user open to the free atmosphere, said receiving means comprising an 80 element for precluding pressure of the medium within said receiving means, said apparatus in use being spaced from such object by the free atmosphere.

5. Apparatus for use with a sound receiving object, comprising means for silently receiving sound waves emitted through the mouth of the user, said receiving means comprising a mouth piece constructed to inclose the mouth of the user but leaving the nose of 90 the user open to the free atmosphere, said receiving means being provided with a plurality of passages leading from the interior of said receiving means to the free atmosphere, said apparatus in use being spaced 95 from such object by the free atmosphere.

6. Apparatus for use with a sound receiving object, comprising means for silently receiving sound waves emitted through the mouth of the user, said receiving means comprising a mouth piece constructed to inclose the mouth of the user but leaving the nose of the user open to the free atmosphere, said receiving means being provided with a plurality of passages extending in 100 a plurality of directions, and connecting the interior of said receiving means with the free atmosphere, said apparatus in use being spaced from such object by the free atmosphere.

7. Apparatus for use with a sound receiving object, comprising means for silently receiving sound waves emitted through the mouth of the user, said receiving means comprising a mouth piece constructed to inclose the mouth of the user but leaving the nose of the user open to the free atmosphere, said receiving means being provided with a plurality of passages leading from the interior of said receiving means to the 115 free atmosphere, and a yieldable diaphragm mounted within said receiving means, said apparatus in use being spaced from such object by the free atmosphere.

8. Apparatus for use with a sound receiving object, comprising means for silently receiving sound waves emitted through the mouth of the user, said receiving means comprising a mouth piece constructed to inclose the mouth of the user but leaving the 120

130

- nose of the user open to the free atmosphere, said receiving means being provided with a plurality of passages extending in a plurality of directions and connecting the interior of said receiving means with the free atmosphere, and a yieldable diaphragm mounted within said receiving means, said apparatus in use being spaced from such object by the free atmosphere.
- 10 9. The combination with a sound receiving device having a member provided with a sound receiving passage, of an apparatus comprising a casing, means disposed in said casing for transmitting sound waves corresponding to the waves emitted through the mouth of the user, and a mouth piece for said apparatus constructed to substantially completely inclose the mouth of the user but leaving the nose of the user open to the free atmosphere, said casing being provided with an exit opening, said exit opening being spaced from said member through the free atmosphere.
- 15 10. The combination with a sound receiving object having a member provided with a sound receiving passage, of a device comprising a casing, means disposed in said casing for transmitting the sounds corresponding to the waves emitted through the mouth of the user, a yieldable diaphragm mounted within said transmitting means and a mouth piece for said casing constructed to substantially completely inclose the mouth of the user but leaving the nose of the user open to the free atmosphere, said device being provided with an exit

opening positioned relatively to said diaphragm oppositely of said mouth piece, said exit opening being spaced from said member through the free atmosphere.

40

11. The combination with a sound receiving object having a member provided with a sound receiving passage and further provided with a yieldable diaphragm, of a device comprising a casing, means disposed in said casing for transmitting the sounds corresponding to the waves emitted through the mouth of the user, a sound responsive diaphragm mounted within said casing and a mouth piece for said casing constructed to substantially completely inclose the mouth of the user but leaving the nose of the user open to free atmosphere, said casing being provided with an exit opening, said exit opening being spaced from said member through the atmosphere.

45

12. A device for use with a sound receiving object, having a member provided with a sound receiving passage and further provided with a sound responsive vibratable element, comprising a casing, and a mouth piece for said casing constructed to substantially completely inclose the mouth of the user but leaving the nose of the user open to the free atmosphere, said casing being provided with an exit opening, said exit opening when the casing is in use being spaced from said member through the free atmosphere.

50

13. In testimony whereof I have signed this specification.

MAXIMILIAN WEIL.
